UNITED STATES PATENT OFFICE.

LORENZO D. TUCKER, OF FERNANDO, CALIFORNIA.

CULTIVATOR.

No. 836,156.

Specification of Letters Patent.

Patented Nov. 20, 1906.

Application filed December 13, 1905. Serial No. 291,627.

To all whom it may concern:

Be it known that I, LORENZO D. TUCKER, a citizen of the United States, residing at Fernando, county of Los Angeles, State of California, have invented and discovered a new and useful Improvement in Cultivators; and I do hereby declare the following to be a full, clear, and exact description of the invention, such as will enable others skilled in the art to 10 which it appertains to make and use the same.

This invention relates to improvements in cultivators; and the objects of my improvement are, first, to provide an agricultural implement having one or more cultivator-blades and a wheel attached to the frame of the cultivator for facilitating the movement of the cultivator when in use.

The invention consists, essentially, in the construction, combination, and arrangement of the several parts, as will be hereinafter described in the specification, shown upon the drawings appended hereto, and specifically pointed out in the claims made a part hereof.

I attain these objects by the construction and mechanism illustrated in the accompanying drawings, in which—

Figure 1 is a view in elevation of parts of my improved implement, portions thereof shown in full lines and other parts thereof illustrated in dotted lines. Fig. 2 is a plan view of the handles of my improved implement, portions thereof broken away, the pushing breast-piece, the furrow-marker, parts thereof shown in full and portions thereof in dotted lines. Fig. 3 is a view in elevation of the pushing breast-piece shown in full and dotted lines, secured to the frame, the handles of my improvement, the furrow-marker pivoted to the frame and parts of the frame, the other portions thereof broken away. Fig. 4 is a view in elevation of portions of my improvement, parts thereof broken away, the plows, cultivator-blades, and harrow-teeth shown connected therewith. Fig. 5 is a view in elevation of portions of my improvement, parts thereof broken away, the plows, cultivator-blades, and harrow-teeth shown connected therewith. Fig. 6 is a view in elevation of my improvement, parts thereof broken away, showing the plows and cultivator-blades connected therewith. Fig. 7^a is a view of the plate to which the harrow-teeth are connected and 55 by means of which the harrow-teeth are se-

cured to the frame of my improved implement. Figs. 7 and 8 are plan views of my improved implement, showing portions of the frame and wheel, other portions thereof broken away, the plows and cultivator-blades 60 secured to the frame; and Figs. 9 and 10 are plan views of the rear portion of my improved implements, showing portions of the frame and wheel, other parts thereof broken away, illustrating the plows, cultivator-blades, and 65 harrow-teeth secured to the frame.

Similar reference numerals, letters, and characters refer to like parts throughout the several views of the drawings.

The numerals 1 1 denote the upper members or legs of the angular side pieces of the frame A, and the numerals 2 2 refer to the lower members or legs of the said angular side pieces of said frame A, the said upper and lower members of the frame A being prefer- 70 ably made in one piece, and at the apices or junctions of the said members or legs 1 1 and 2 2 of the said side pieces of the frame A the axle 3 of the wheel 4 is provided with bearings 5 5, and upon the extended ends of the 80 axle 3 on the outside of the frame A the draft-hooks 6 6 are secured by means of nuts 7 7. To these draft-hooks 6 6 the tugs or traces of the harness of a horse or horses are attached whenever required to draw the com- 85 bined plow, cultivator, harrow, and seeder from place to place.

The curved end pieces 12 12 of the frame A are fastened at their upper ends to the upper ends of the members or legs 1 1 of the frame 90 by means of the headed screw-bolts or rivets 13 13, as illustrated upon Figs. 1, 2 and 3 of the drawings, and the lower ends of the curved end pieces 12 12 are secured to the rear ends of the members or legs 2 2 of the side 95 pieces of the frame A in like manner by means of headed screw-bolts or rivets 14 14, as shown upon Figs. 1, 4, 7, 8, 9, and 10 of the drawings. The said members or legs 2 2 of the side pieces of the frame A for the greater 100 portion of their length extend parallel with each other, as illustrated upon Figs. 1, 4, 5, 6, 7, 8, 9, and 10 of the drawings, and near the rear ends of said members or legs 2 2 are provided with angular inturned portions 15 105 15, and the end portions 16 16 of the said members or legs 2 2 again extend parallel with each other, forming a narrow space 17 therebetween, in which the beams 18 and 19 of one of the plows 18' and 19', respectively, 110

are fastened (one of said plows being smaller than the other and arranged in parallel lines with each other) by means of the headed screw-bolts 20 20 and nuts 21 21, as shown 5 in the figures of the drawings. A double-moldboard plow may be used in place of the plows 18' and 19'.

The plows 29' 29' (shown upon Figs. 1 and 6 of the drawings) and the cultivator-blades 10 25" 25" have their shanks 26 26 bent at right angles to the members or legs 2 2 of the frame A, as shown at 27 upon Figs. 1, 4, 5 and 6 of the drawings.

All the shanks of the plows 29 29 and all of 15 the shanks of the cultivator-blades 29" 29" are secured to the members or legs 2 2 of the frame A by means of slotted disks 30 30, as illustrated upon Figs. 1, 4, 5, 6, and 10 of the drawings. These slotted disks 30 30, bolted 20 to the beams of all the plows and cultivator-blades secured to the members 2 2 by means of rivets or screw-bolts 31 31, permit the plows and cultivator-blades to be thrown in the elevated position, as shown upon various 25 views of the drawings, or in the position to turn the earth, as illustrated upon Figs. 1, 6, and 10 of the drawings, the headed bolt 32 being arranged in the slots 33 33, the said slots 33 33 being moved upon the said bolts 32 32 30 when the plows and cultivator-blades are raised and lowered.

The beams 18 and 19 of the rear end plows 18' and 19', respectively, (shown upon Fig. 7 of the drawings,) have secured thereto 35 slotted disks 30 30, which are clamped in the space 17 between the extended ends of the members 2 2 by means of headed bolts 32 32.

The harrow-teeth 35 35 (shown upon Figs. 4 and 5 of the drawings) are secured at their 40 front ends to the plate 36 by means of bolts or rivets, the said plate 36 being bent twice upon itself at right angles, as illustrated upon Fig. 7^a of the drawings, forming a rectangular opening in the front free end of said plate, 45 adapted to be secured upon the inturned ends 15 15 of the members or legs 2 2, as illustrated in Figs. 8, 9, and 10 of the drawings.

The handles 40 40 of my improved implement are pivoted at 60 to the curved end 50 pieces 12 12 of the frame A. The front ends of the said handles 40 40 are swiveled at 61 upon pins to the links 62 62, and the said links 62 62 are connected by means of pins 63 63 in slots 64 64 in the upright members or legs 1 1 55 of the frame above the journal 3, on which the wheel 4 of the implement revolves. The said handles 40 40 can be raised and lowered, as shown in dotted lines upon Fig. 1 of the drawings, and the said links 62 62 can also be 60 raised or lowered by moving the pin 63 in the slot 64, the pin 61 bearing against the rear edge of the member or leg 2 of the frame.

The numeral 67 denotes the pushing breast-piece, which is longitudinally extensible, as shown in dotted lines upon Fig. 3 of

the drawings. The said pushing breast-piece 67, slidably connected to the rod 68, which is swiveled to the cross-head 69' of the frame, as shown upon Fig. 2 of the drawings, is held at any point thereon by the thumb-screw 69. The said improved pushing breast-piece I employ for moving the implement from place to place. The said longitudinally-adjustable breast-piece 67 is secured in place when not in use within the keeper 70, having 70 a pivoted button 71 (shown upon Fig. 3 of the drawings) secured to the keeper, as shown 75 upon Figs. 1 and 2 of the drawings.

Having been required to divide out of this application the plows, the harrow-teeth, the 80 seeder, and the land-marker, I hereby reserve the right to file separate applications for patents for each of the subjects-matter required to be divided out of this my original application. 85

From the foregoing description, taken in connection with the accompanying drawings, it is thought that the construction, mode of operation, and advantages of my invention will be readily apparent without requiring further extended explanation. 90

Various changes in the form, proportion, and minor details of construction may be resorted to without departing from the principle or sacrificing any of the advantages of 95 this invention, and I therefore reserve to myself the right to make such changes as fairly fall within the scope thereof.

What I do claim as my invention, and desire to secure by Letters Patent, is— 100

1. A cultivator comprising a frame having parallel angular side pieces, the curved end pieces secured to the free ends of said angular side pieces, a wheel journaled at the angle of said side pieces, cultivator-blades adjustably secured to said side pieces and adjustable handles movably secured to said side pieces and pivoted to the said end pieces. 105

2. A cultivator comprising angular side pieces, curved end pieces fastened to the free 110 ends of said side pieces, a wheel journaled at the angle of said side pieces, blades secured to the said angular side pieces and vertically-adjustable handles movably secured to said side pieces and pivoted to said rear end 115 pieces.

3. A farming implement comprising a frame having upright parallel legs and lower inclined parallel legs, curved end pieces fastened to the free ends of said legs, a wheel 120 journaled at the junction of said upright and inclined members, cultivator-blades adjustably connected to the lower inclined member of the frame, adjustable handles pivoted to the curved end pieces and adjustably secured 125 to the upright members of said frame.

4. An agricultural implement comprising a frame provided with upright parallel legs and lower inclined parallel legs, curved end pieces fastened to the free ends of said legs, a 130

wheel journaled at the junction of said upright and inclined members, cultivator-blades adjustably connected to said inclined legs of the frame, vertically-adjustable handles pivoted to the said curved end pieces near the front ends thereof, and provided with swiveled links movably connected to said upright parallel legs.

5. A farming implement comprising a frame having upright parallel legs and lower inclined parallel legs and curved end pieces secured to the free ends of said upright parallel legs and to the free ends of the lower inclined parallel legs of the frame, a wheel journaled in the front end of the frame, handles pivotally secured to the said curved end pieces and having swiveled links movably fastened to the said upright legs of the frame, a longitudinally-adjustable pushing breast-piece secured to the upper and free ends of the said upright parallel legs, cultivator-blades adjustably secured to the lower inclined legs of the frame.

6. An agricultural implement having a frame comprising upright parallel legs, lower inclined parallel legs and curved end pieces, the said curved end pieces fastened to the ends of said upright parallel members and the lower inclined members of the frame, a wheel journaled in the lower front end of the frame, cultivator-blades connected to the lower inclined legs, vertically-adjustable handles connected to the frame and a longitudinally vertically adjustable pushing breast-piece pivotally connected to the frame.

7. An agricultural-implement frame comprising upright, parallel members, lower inclined, parallel legs, curved end pieces fastened to the free ends of said legs, a wheel journaled at the junction of said upright, parallel members and said inclined, parallel legs, said frame carrying devices for turning up the ground, and means for propelling said implement.

8. An implement comprising a frame having upright parallel legs and lower inclined legs and curved end pieces secured to the free ends of said upright parallel legs and to the free ends of the lower inclined legs of the frame, a wheel journaled in the front end of the frame, a series of cultivator-blades swiveled to the sides and ends of the frame and means for moving the implement from place to place.

9. An implement comprising a frame having upright parallel legs and lower inclined parallel legs and curved end pieces secured to the free ends of said upright parallel legs and to the free ends of the lower inclined legs of the frame, a wheel journaled in the front end of the frame, cultivator-blades swiveled to the sides and ends of the frame and means for conveying the implement from place to place.

10. An implement comprising a frame having upright parallel members and lower inclined parallel members and curved end pieces secured to the free ends of said upright parallel members and to the free ends of the lower inclined parallel members of the frame, a wheel journaled in the front end of the frame, handles pivotally secured to the said curved end pieces and having swiveled links movably fastened to the said upright parallel members of the frame and a longitudinally-adjustable pushing breast-piece secured to the upper and free ends of the said upright and parallel members and cultivator-blades swiveled to the sides and ends of the frame.

In testimony whereof I have signed my name to this specification in the presence of two subscribing witnesses.

LORENZO D. TUCKER.
